SAFETY ENVELOPE AND BLANK FOR MAKING THE SAME

Filed Feb. 16, 1923

WITNESS: *J. B. Swartz*

Mortimer L. Hinchman
INVENTOR:
BY *Victor J. Evans*,

ATTORNEY.

Patented Oct. 14, 1924.

UNITED STATES PATENT OFFICE.

MORTIMER L. HINCHMAN, OF BROOKLYN, NEW YORK.

SAFETY ENVELOPE AND BLANK FOR MAKING THE SAME.

Application filed February 16, 1923. Serial No. 619,477.

To all whom it may concern:

Be it known that I, MORTIMER L. HINCHMAN, a citizen of the United States, residing at Brooklyn, in the county of Kings and State of New York, have invented new and useful Improvements in Safety Envelopes and Blanks for Making the Same, of which the following is a specification.

This invention relates to envelopes.

More particularly, the invention relates to envelopes of the kind disclosed in United States Letters Patent Nos. 598,290, 641,291, 717,993, 780,883, and 1,351,851, granted to me.

Some of the objects of the present invention are: to improve envelopes of the kind mentioned by simplifying the same without sacrificing of the factor of safety hitherto attained; to produce a blank for making a safety envelope which is of such form and construction as to facilitate the formation of an envelope in the despatch of a letter; to produce an envelope which is absolute proof against persons having a willful disregard of the rights of another; and with these and other objects in view the invention resides in the particular manner of forming an envelope, the overlapping relation of parts and the functions of features thereof hereinafter fully described and illustrated in the accompanying drawing, in which:

Figure 1 is a view of the envelope-blank of the present invention.

Figure 2 is a view showing two of the back folds folded over.

Figure 3 is a view showing the formed envelope opened.

Referring now more particularly to the several views of the drawing, and especially Figure 1, it will be apparent that a blank is made first, such as the blank 10, from which the envelope 11 is made. The blank 10 has all the attributes, to be presently described, for the making of a safety envelope. The blank 10 is made from a single piece of material of any kind, and in fact is stamped out of the material to provide a front fold 12, a seal flap 13 on the front fold 12, and back folds 14, 14, and 15 on the front fold. The front fold 12 embodies a partly severed portion 16 by virtue of the perforations 17 and 18, where as, the seal flap 13 embodies a partly severed portion 19 by virtue of the per-

forations 17 and 20. The portions 16 and 19 adjoin each other. The perforations 17 are in the line of fold between the front fold and the seal flap. The back folds 14, 14, are of the same shape and size, there being one at each end of the front fold 12. Each fold 14 has a line of perforations 21 and a line of perforations 22, thus providing perforations along the edges of the folds 14, 14. The back fold 15 is at the side of the front fold opposite the seal flap. The fold 15 has a line of perforations 23 and a line of perforations 24, thus providing the fold 15 with perforations along the free edges thereof. The marginal portion of the seal flap between the perforations thereof and its free edges is gummed as at 25. The marginal portions of the back fold 15 between the perforations thereof and the adjacent free edges are gummed as at 26. The back folds 14, 14, and 15 are folded over the front fold respectively on the fold lines 27, 27, and 28.

To form an envelope the back folds 14, 14, are first folded over the front fold 12, and then the back fold 15 is folded over the back folds 14, 14, and that of course is done after the gummed portions 26 have been moistened. Under the relation of the back folds the lines of perforations 22 will lie substantially mid-way of the gummed portions 26 longitudinally thereof. When the seal flap 13 is brought into sealing relation with portions of the back folds in the despatch of a letter after the moistening of the gummed portion 25, the perforations 21 of the back folds 14, 14, will lie substantially mid-way of the gummed portion 25.

It will now be manifest that, due to the overlapping relation of the several folds and the disposition of the perforations therein, it will be well nigh impossible to steam the seams formed to effect an entry without permanent destruction of portions of the folds at the points steamed; that pointed instruments will only pick up the portions at the seams because of the perforations; and that the addressee by moistening the perforations 17 may thumb the portion 16 or the portion 19 to roll the same as shown in Figure 3 for the opening of the envelope.

What is claimed is:

1. A blank for making a safety envelope comprising a front fold, back folds, a seal

flap, a partly severed portion embodied by the front fold and the seal flap, the marginal portion of said seal flap being gummed, and each of said back folds provided with a plurality of free marginal edges and having perforations along said edges.

2. A blank for making a safety envelope comprising a front fold, back folds, each of which is provided with a plurality of free marginal edges and having perforations along said edges, one back fold at each end of the front fold and at one side of the front fold, a seal flap at one side of the front fold, a partly severed portion in the front fold and in the seal flap, the severed portions being

adjoined, and the seal flap having a marginal gummed portion.

3. An envelope comprising a front fold, back folds each of which is provided with a plurality of free marginal edges and having perforations along said edges and portions of one back fold overlapping portions respectively of the other back folds, and a seal flap on the front fold having marginal perforations and gummed between said perforations and the adjacent edges for securing the back shoulder in operative position.

In testimony whereof I hereby affix my signature.

MORTIMER L. HINCHMAN.
